UNITED STATES PATENT OFFICE.

TYSON C. SWARTZ, OF FAIRVIEW, ILLINOIS.

REPLANTING ATTACHMENT FOR CULTIVATORS.

No. 835,958.

Specification of Letters Patent.

Patented Nov. 13, 1906.

Application filed April 10, 1906. Serial No. 311,004.

To all whom it may concern:

Be it known that I, TYSON C. SWARTZ, a citizen of the United States, residing at Fairview, in the county of Fulton and State of Illinois, have invented new and useful Improvements in Replanting Attachments for Cultivators, of which the following is a specification.

This invention relates to corn-planters, the object of the invention being to provide a device for replanting corn and other seed, which is adapted to be applied to any style of cultivator, either riding or walking, and also adapted to be operated by hand, at the places where it is necessary to effect a replanting.

A further object of the invention is to provide a corn-planter which after being tripped by a suitable hand device is automatic in its action of measuring off the desired number of grains and depositing them in the furrow formed by the shoe of the planter.

With the above and other objects in view the invention consists in the novel construction, combination, and arrangement of parts, hereinafter more fully described, illustrated, and claimed.

In the accompanying drawings, Figure 1 is a perspective view of a cultivator with the improved planting device applied thereto. Fig. 2 is an enlarged plan view of the planter. Fig. 3 is a side elevation of the same. Fig. 4 is a detail section of the lower end of the seed-tube. Fig. 5 is a side elevation similar to Fig. 3 showing the manner in which the frame tilts to discharge the corn. Fig. 6 is a sectional view through the hopper with the parts in the position shown in Fig. 5. Fig. 7 is a sectional plan view of the hopper, showing the cut-off.

In the drawings I have shown the corn-planter applied to an ordinary walking-cultivator embodying the usual beam 1, clevis 2, standard 3, shovel 4, handles 5, and handle-bars 6.

In carrying out the present invention I employ an L-shaped bracket 7, which may consist of a rod or piece of tubing bent into the form of an L, having the upright or vertical portion 8 thereof connected to the cultivator-beam by means of a clip 9, the bracket being thus held rigidly to the beam with the horizontal portion of the bracket extending laterally away from the beam to any desired distance and forming a shaft or supporting-axle upon which the frame of the corn-planter is journaled and permitted to

tilt in the manner hereinafter particularly described.

The tilting frame of the corn-planter embodies the oppositely-arranged and substantially parallel side bars 10, provided with bearings 11, which embrace the horizontal portion of the bracket 7 and turn thereon, said side bars being connected by a front cross-bar 12. At the inner side of the tilting frame there is arranged a stop-collar 13, while at the outer side of said frame is arranged another stop-collar 14, from which a rigid arm 15 projects horizontally forward, the forward extremity of said arm being bent inward, as shown at 16, to provide for the connection therewith of a retracting-spring 17, the opposite or rear end of which is connected to the cross-bar 12 of the tilting frame, as shown at 18. The spring 17 exerts its tension to hold the tilting frame normally in the position shown in Fig. 3—that is to say, in a substantially horizontal position, while permitting the frame to tilt for a purpose hereinafter described.

Mounted between the rear ends of the side bars 10 of the tilting frame is a hopper 19, provided with a suitable lid or cover 20. This hopper is pivotally mounted at 21 between the rear ends of the side bars 10 of the tilting frame, so that it may rock between said arms, and, as shown in Fig. 6, the bottom of the hopper is provided with a discharge-opening 22, communicating with which is a dropping-tube 23, which is rigidly connected to the bottom of the hopper and extends downward a suitable distance therefrom. Mounted upon the tube 23 is an extension-tube 24, which is adjustable up and down on the tube 23 and adapted to be held by means of a binding-screw 25, thus enabling the height of the furrow-forming shoe 26 to be regulated, the shoe 26 being rigidly connected to and carried by the lower adjustable tube 24.

Operating over and upon the bottom of the hopper is a seed-slide 27, which is provided at a suitable point with a pocket 28, movable beneath a guard 29, which covers the pocket 28 when said pocket is in line with the discharge-opening 22 in the bottom of the hopper. When the slide 27 moves forward, the pocket 28 is moved from beneath the guard 29 and placed in communication with the hopper, so as to receive the necessary number of grains of corn, and as the slide is moved rearward again to carry

the pocket beneath the guard the guard acts as a cut-off for the corn, permitting only the requisite number of grains to pass under the same and be delivered into the tube 23.

5 The slide 27 operates through oppositely-arranged slots 30 in the hopper, and the rear end of said slide is pivotally connected at 31 to a pair of oppositely-arranged links 32, which pivotally connect at 33 with the side bars 10 of the tilting frame. Stops 34 project outwardly from the sides of the hopper and are adapted to come in contact with the side bars 10 for limiting the rocking movement of the hopper when it reaches the position shown in Figs. 5 and 6, at which time the pocket 28 is in line with the discharge-opening 22. The spring 17 acts to retract the tilting frame to the position shown in Figs. 1 and 3, and as the tilting frame re- 10 sumes its horizontal position the links 32 operate to return the hopper 19 to its normal vertical position, at the same time restoring the tube 23 and the parts connected therewith to the normal position. The forward 15 portion of the tilting frame is provided with a laterally-extending L-shaped lever-arm 35, from which a connecting-rod 36 extends backward to a hand-lever 37, which is pivotally mounted at 38 on one of the handles or 20 handle-bars, as shown at Fig. 1, thus placing the same in convenient position to be operated by the attendant for throwing the corn-planter into operation, in the manner above explained. It will be seen that after the operator moves the tilting frame sufficiently to 25 cause the shoe 26 to engage the ground the remainder of the operation is automatic, the shoe serving to swing the tilting frame to the limit of movement.

In order to balance the hopper 19 in a substantially upright position, as shown in Figs. 1 and 3, I employ a balancing-spring 39, which is connected at one end to a lug 40, projecting outward from one side of the hopper, and at its other end to a fixed point on 45 the bracket 7, which may consist of a pin 41 on the collar 14, hereinabove described. The spring 39 in connection with the spring 17 serves to restore all of the movable parts of the mechanism to their normal inactive 50 position as soon as the shoe 26 moves upward out of engagement with the ground.

I claim—

The herein-described replanting attachment for corn-planters consisting of a supporting-bracket, means for securing said bracket to the frame of a planter, a tilting open-center frame having the side bars thereof journaled on said supporting-bracket, a spring for holding said tilting frame yielding in a substantially horizontal position, a hopper pivotally mounted in said tilting frame, means for balancing said hopper and for holding it in a normally upright position, a seed-slide mounted in said hopper, a dropping-tube extending downward from the hopper and carried thereby, a link connecting said slide and the tilting frame, whereby the slide is operated simultaneously with the swinging of the tilting frame, and a guard 60 extending over the opening in the seed-slide and pocket,

In testimony whereof I affix my signature in presence of two witnesses.

TYSON C. SWARTZ.
